Des. 210,357

Patented Mar. 5, 1968

210,357

MODULAR BUILDING

Roy E. Anderson, 6404 Atlantic Ave.,
Ventnor, N.J. 08406

Filed Nov. 21, 1966, Ser. No. 4,744

Term of patent 14 years

(Cl. D13—1)

FIG.1

FIG.3

FIG.4

FIG.2

FIG.5

FIG. 6

FIG. 7

FIG. 8

FIG. 9

FIG. 10

FIG. 11

FIG.12

FIG.13

FIG. 14

FIG. 15

FIG. 16

FIG. 17

FIGURE 1 is an elevation view of one face of a modular building showing my new design;

FIGURE 2 is an elevation view of a face adjacent to that shown in FIGURE 1;

FIGURE 3 is a top plan view of a building in accordance with my new design;

FIGURE 4 is a bottom view of a modular building in accordance with FIGURES 1 to 3.

FIGURE 5 is a perspective view of a modular building in accordance with FIGURES 1 to 4, omitting for clarity those portions of such figures which appear in broken lines.

FIGURE 6 is an elevation view of one face of another embodiment of a modular building embodying my novel design;

FIGURE 7 is an elevation view of a face adjacent to that shown in FIGURE 6;

FIGURE 8 is an elevation view showing a face opposite that shown in FIGURE 6;

FIGURE 9 is a top plan view of the modular building in accordance with FIGURES 6-8;

FIGURE 10 is a bottom view of a modular building in accordance with FIGURES 6 to 9;

FIGURE 11 is a perspective view of a modular building in accordance with FIGURES 5-10, omitting for clarity those portions of such figures which appear in broken lines;

FIGURE 12 is an elevation view of one face of still another embodiment of a modular building incorporating my novel design;

FIGURE 13 is an elevation view of a face adjacent to that shown in FIGURE 12;

FIGURE 14 is an elevation view of a face of a modular building opposite that shown in FIGURE 13;

FIGURE 15 is a top plan view of the modular building of FIGURES 10-14;

FIGURE 16 is a bottom view of a modular building in accordance with FIGURES 12 to 15;

FIGURE 17 is a perspective view of a modular building in accordance with FIGURES 12 to 16, omitting for clarity those portions of such figures as appear in broken lines;

The faces not specifically illustrated are mirror images of those opposite thereto.

The broken-away portion in FIGURES 6 and 8 is identical in appearance to the corresponding portion in FIGURE 7.

The broken-away portion in FIGURES 12 and 14 is identical in appearance to the corresponding portion in FIGURE 13.

The dominant features of my design reside in the portions shown in full lines.

I claim:

The ornamental design for a modular building, substantially as shown and described.
